UNITED STATES PATENT OFFICE.

LOUIS FOX, OF FORT WAYNE, INDIANA, ASSIGNOR TO THE NATIONAL BISCUIT COMPANY, OF CHICAGO, ILLINOIS.

DESIGN FOR A CRACKER OR BISCUIT.

SPECIFICATION forming part of Design No. 31,777, dated October 31, 1899.

Application filed October 9, 1899. Serial No. 733,106. Term of patent 14 years.

To all whom it may concern:

Be it known that I, LOUIS FOX, a citizen of the United States, residing at Fort Wayne, in the county of Allen and State of Indiana, 5 have invented and produced a new and original Design for Crackers or Biscuits, of which the following is a specification, reference being had to the accompanying drawings, in which—

- Figure 1 is a plan view of a cracker or biscuit embodying my design, and Fig. 2 is a cross-sectional view of the same on the line 2 2 of Fig. 1.

The leading feature of my design consists 5 in the configuration or external contour of the cracker, the same being rectangular in general form and one of its sides having a protuberance with a curved outline and its opposite side having a scallop bounded by a 10 curved line, thereby producing the effect of a rectangular figure whose body portion on opposite sides of a central line taken through

the body is displaced, the irregular portions being bounded by curves.

A represents the body of the cracker, two 25 of whose parallel sides *a* are straight. *c* represents straight portions of another side of said body, said straight portions being joined by the curved portion *b*. *d* represents straight portions of the remaining side, joined 30 by the entering curve *e*, defining a scallop in one edge of the body.

As a subordinate or subsidiary feature of said design the margin is crimped, as shown at *f*, while upon its top are shown rounded 35 depressions *g*.

I claim—

The design for a cracker or biscuit substantially as shown and described.

LOUIS FOX.
